UNITED STATES PATENT OFFICE.

LAURENCE R. DAVIS, OF PROVIDENCE, RHODE ISLAND, ASSIGNOR TO REVERE RUBBER COMPANY, A CORPORATION OF RHODE ISLAND.

DESIGN FOR AN ELASTIC VEHICLE-TIRE.

53,410.

Specification for Design. Patented June 10, 1919.

Application filed January 15, 1917. Serial No. 142,570. Term of patent 14 years.

To all whom it may concern:

Be it known that I, LAURENCE R. DAVIS, a citizen of the United States, residing in the city of Providence, county of Providence, State of Rhode Island, have invented a new, original, and ornamental Design for an Elastic Vehicle-Tire, of which the following is a specification, reference being had to the accompanying drawing, forming a part thereof.

Figure 1 of the drawing represents a per-

spective view of a vehicle tire showing my new design, mounted on a rim;

Fig. 2 is a cross section taken on the line 2—2 of Fig. 1 and

Fig. 3 is a fragmentary longitudinal section taken on the line 3—3 of Fig. 1.

I claim:

The ornamental design for an elastic vehicle tire, as shown.

LAURENCE R. DAVIS.
